Attnys.

UNITED STATES PATENT OFFICE.

JAMES ERNEST MANN, OF SALEM, MASSACHUSETTS, ASSIGNOR TO PARKER BROTHERS, INC., OF SALEM, MASSACHUSETTS, A CORPORATION OF MAINE.

GAME

1,411,574.

Specification of Letters Patent.

Patented Apr. 4, 1922.

Application filed May 25, 1921. Serial No. 472,407.

To all whom it may concern:

Be it known that I, JAMES ERNEST MANN, a citizen of the United States, and a resident of Salem, in the county of Essex and State of Massachusetts, have invented an Improvement in Games, of which the following description, in connection with the accompanying drawings, is a specification, like characters on the drawings representing like parts.

This invention relates to games and more particularly to games wherein pieces or blocks, preferably cubical, are employed having letters upon their several faces, preferably spelling a word and adapted to control or determine the movement of pieces upon or about a board.

In order that the principle of the invention may be readily understood, I have disclosed a single embodiment thereof in the accompanying drawing, wherein—

Fig. 1 is a plan view of a board having spaces, which is merely typical of the use or adaptation of my invention;

Fig. 2 is a view of the cup or holder that may be employed;

Fig. 3 is a view of the pieces or certain thereof that may be employed in playing the game;

Fig. 4 is a plan view of the blocks which in the present instance are six in number; and

Fig. 5 is a perspective view of one of the blocks.

Referring more particularly to the drawing, I have indicated the board at 1. It may be of any suitable character, and desirably is a folding one, though this is immaterial so far as the principle or adaptation of my invention is concerned. The board is provided with any suitable number of spaces, which in the present instance are indicated generally at 2, and in this embodiment of the invention are arranged as an ellipse like

an ordinary race track, the start and finish being indicated at 3. It is, however, to be understood that the spaces may be arranged in any suitable way so long as the pieces can be moved from the space or spaces where the game is commenced to the finish. It is not essential to the principle of the invention that the pieces of the several players move over the same track or course, as within the scope and purpose of my invention, the pieces may be moved as desired provided

the movements are controlled by throws of the blocks or members indicated at 4 in Figs. 4 and 5.

In accordance with the broad principle of my invention I provide blocks 4, which are desirably, but not necessarily cubical, and desirably upon each of the faces of each block I place a letter, which desirably together form a word. Within the scope and purpose of my invention, one or more of the faces of each block may be left blank or contain some matter which is other than a letter. While the letters are desirably so selected as to combine into a word, it is evident that within the principle of my invention, the letters may be certain consecutive letters of the alphabet, as, for example, A, B, C, D, E and F. Desirably the letters of each block form a word and in the present instance, they spell the word "MOVIES." I may, however, select letters spelling some other word, such, for example, as the word "PONIES," it being noted that the drawing represents a horse racetrack. In the event that one of the faces of each block is left blank, it is evident that where the blocks are cubical, there would be but five letters employed which may spell a word, such, for example, as "MOVIE" or "HORSE." It is within the scope of my invention to leave more than one face of each block blank, and particularly if the block have more faces than six.

Assuming for example, that cubes are used and five of the faces are provided with a letter, the sixth space may contain some emblem or other mark, such, for example, as a star, the significance of the star or other mark when shown implying, for example, the right to another throw of the blocks, or an extra move forward of one piece or some other privilege having to do with the moving of the pieces upon the board or the throwing of the pieces. These and other advantages are all within the scope and spirit of my invention, since so far as I am aware, the principle herein set forth is an entirely new one in governing the moves upon a board or like game spaced for the moving of pieces.

Other variations of the principle of my invention may be made.

The pieces are indicated at 5 in Fig. 3. These may be of any suitable character, and any suitable number may be used. I have

herein represented two, but four are desirably provided, and thus, two, three or four players may take part in the game, or the game may be played as a solitaire game.

5 At 6, I have represented a cup or holder in which the blocks may be assembled and from which they may be discharged after the manner of dice.

While rules governing the game may be 10 variously formulated, preferably and assuming that there are four players and six blocks, the game is desirably played as follows:

The players throw the blocks to determine 15 who starts the game, the one throwing the largest number of single letters spelling the word "MOVIES" starting, the playing going to the left. The letter "M" must always appear to make any count, it being the first 20 letter of the word "MOVIES." If the letter "O" also appears, the player moves two spaces; if "V" appears three spaces, and so on. Only one move can be made for each letter. In other words, in order to move six 25 spaces, it is necessary for all six letters to appear at one throw. In commencing the play, all the blocks 4 are placed in the cup or holder 6, and the blocks are shaken and thrown onto the table. The play is made 30 according to the number of letters that appear forming the word "MOVIES," and these letters must appear in consecutive order to count. If, for example, a player throws "MOIIES," he would move two 35 spaces only, because he has gotten an "M" and an "O" and no "V." If he throws "MEVIES," he can only move one space, as no letter appears in consecutive order with the letter "M." To have the letter "V" 40 count, it would be necessary for an "O" to appear in this throw. In other words, the letters must appear in consecutive order to count. If no letter "M" is thrown, no play can be made. If a player throws all six letters 45 of the word "MOVIES," he is entitled to move his playing pieces six spaces. Only one throw of the blocks is permitted each player in turn. The person first getting his or her piece into the space at the center of 50 the board or such other space as may be determined according to the spacing of the board, wins the game.

The "home" space must, however, be reached by an exact throw of the blocks. 55 If a player should be on a space which is three from the "home," he must throw an "M," an "O" and a "V" to reach "home." If the letter "I" also appears in that throw, the player loses his turn, as this would make a 60 four space move necessary. If, however, the throw shows the letter "M" or the letters "M" and "O," he is entitled to move one space in the former case and two in the latter.

65 So far as I am aware, I am the first to em-

ploy a board or like game having spaces for movement of a piece or pieces thereon, the movements of such piece or pieces being governed or determined by blocks or like members having letters on their several 70 faces, whether or not the blocks are cubical and whether or not the several letters of each block spell a word.

Having thus described one illustrative embodiment of my invention, I desire it to 75 be understood that although specific terms are employed, they are used in a generic and descriptive sense and not for purposes of limitation, the scope of the invention being set forth in the following claims.

Claims:

1. A game having one or more pieces to be moved about a spaced board or the like, and a series of blocks adapted to be thrown to determine the movements of said piece or pieces, each of said blocks having a single letter upon each face, the letters upon all the faces of each block bearing a predetermined relation to each other and the letters upon all the blocks being the same.

2. A game having one or more pieces to be moved about a spaced board or the like, and a series of blocks adapted to be thrown to determine the movements of said piece or pieces, each of said blocks having a letter 95 upon each face, all the letters upon all the faces of each block collectively spelling a word.

3. A game having one or more pieces to be moved about a spaced board or the like, and a series of blocks adapted to be thrown to determine the movements of said piece or pieces, each of said blocks having the same 100 number of faces and each face bearing a letter, all the letters of each block collectively spelling a word.

4. A game having one or more pieces to be moved about a spaced board or the like, and a series of blocks adapted to be thrown to determine the movements of said piece or pieces, each of said blocks being cubical, and each face of each block bearing a letter, the said letters upon each block bearing a 110 sequential relation to each other, the letters upon all said blocks being the same.

5. A game having one or more pieces to be moved about a spaced board or the like, and a series of blocks adapted to be thrown to determine the movements of said piece or pieces, each of said blocks having the same 120 number of faces and the corresponding faces of the series of blocks bearing the same single letter, the letters of each block bearing a sequential relation to each other.

6. A game having one or more pieces to be 125 moved about a spaced board or the like, and a series of blocks adapted to be thrown to determine the movements of said piece or pieces, each of said blocks having the same number of faces and the corresponding faces 130

135

of the series of blocks bearing the same single letter, the letters of each block spelling a word.

7. A game having one or more pieces to be moved about a spaced board or the like, and a series of blocks adapted to be thrown to determine the movements of said piece or pieces, each of said blocks being cubical, and the corresponding faces of the series of blocks bearing the same single letter, the letters of each block together spelling a single word.

8. For use in playing a game wherein pieces are moved, a series of blocks adapted to be thrown to determine the movements of said pieces, each of said blocks having the same number of faces, and each face bearing a single letter, the letters of each block bearing the same sequential relation among themselves as exists among the letters of each the other blocks.

9. For use in playing a game wherein pieces are moved, a series of blocks adapted to be thrown to determine the movements of said pieces, each of said blocks being cubical and bearing a single letter upon each face, the lettering being the same upon all the blocks and the combined letters of each block spelling the same single word, that is characteristic of all the blocks.

10. For use in playing a game wherein pieces are moved, a series of blocks adapted to be thrown to determine the movements of said pieces, each of said blocks being cubical and each block bearing the letters M O V I E S, one only of said letters appearing on a single face.

11. A game having one or more pieces to be moved about a spaced board or the like

and a series of blocks adapted to be thrown to determine the movements of said piece or pieces, each of said blocks having a single letter upon each of a plurality of faces, the letters upon the several lettered faces of each block collectively spelling a word.

12. A game having a board with spaces adapted for the movement of pieces thereon, and a set of blocks adapted to be thrown to govern the movement of said pieces, each of a plurality of faces of each block of said set having a single letter thereon, said letter differing from the other letters upon that block, the said plurality of letters upon each block spelling a word, which is also spelled by the said letters of each of the other blocks, the said blocks being adapted to be thrown and the letters appearing uppermost when the blocks are thrown, governing the play and the movement of the pieces about the board.

13. A game having a board with spaces adapted for the movement of pieces thereon, and a set of cubical wooden blocks adapted to be thrown to govern the movement of said pieces, each face of each block of said set having a single letter thereon, said letter differing from the other letters upon that block, the said plurality of letters upon each block spelling a word, which is also spelled by the said letters of each of the other blocks, the said blocks being adapted to be thrown and the letters appearing uppermost when the blocks are thrown, governing the play and the movement of the pieces about the board.

In testimony whereof, I have signed my name to this specification.

JAMES ERNEST MANN.
